UNITED STATES PATENT OFFICE.

WILLIAM WHIITE, OF PASSAIC, NEW JERSEY, ASSIGNOR TO CLARENCE WHITMAN & CO., OF NEW YORK, N. Y.

DESIGN FOR A BEDSPREAD.

SPECIFICATION forming part of Design No. 26,535, dated January 12, 1897.

Application filed October 10, 1896. Serial No. 608,522. Term of patent 7 years.

To all whom it may concern:

Be it known that I, WILLIAM WHITE, a citizen of the United States, residing at Passaic, Passaic county, State of New Jersey, have 5 invented and produced a new and original Design for Bedspreads, of which the following is a specification.

The leading feature of my design is a bedspread having the following features: an ornamental center, an angular ornamental band embracing the said center and comprising lozenge and cruciform figures, and an ornamental border comprising alternate inclined bands exhibiting plaid or line effects.

15 My design is shown in the accompanying drawing, which shows a quarter-section of the design, the remaining quarter-sections being repetends.

The upper left-hand corner of the figure represents a quarter-section of the centerpiece or 20 center of the design and comprises rectangu-

lar effects *a b c d* and sinuous band effects *e*. Adjacent to the sinuous band effects is a check cruciform figure *f*, which is bordered by a field *g*, presenting a plaited effect. Bordering the 25 field *g* is the aforesaid band, presenting the lozenge and cruciform check effects, shown as consisting of angular check effects *h*, lozenge lattice effects *i*, and cruciform lattice or check effects *j*. Bordering the said band is a border 30 comprising alternate bands *k l*, presenting plaid or line effects.

It is obvious that the detail of the design may be varied.

What I claim is—

35 The design for a bedspread substantially as shown.

WILLIAM WHIITE.
